UNITED STATES PATENT OFFICE.

HERBERT PRICE LAVENDER, OF WALSALL, ENGLAND.

LETTER-FILE.

SPECIFICATION forming part of Letters Patent No. 605,492, dated June 14, 1898.

Application filed May 3, 1897. Serial No. 634,929. (No model.)

To all whom it may concern:

Be it known that I, HERBERT PRICE LAVENDER, a subject of the Queen of England, residing at Walsall, England, have invented certain new and useful Improvements in or Relating to Letter-Files, of which the following is a specification.

This invention relates to the construction of letter-files, its principal object being to enable them to be folded flat, so that they will occupy less space in packing than similar devices made in the manner which has heretofore been customary; and the invention consists in the novel construction, arrangement, and combination of parts, as hereinafter described and claimed.

In the accompanying drawings, Figure 1 is a perspective view of a file constructed according to this invention with its cover turned back, one of the filing arms or wires being indicated by dotted lines in the position to which it is moved when papers are to be put on or taken off the companion wire. Fig. 2 is a similar view of the file with its cover closed and both wires folded down, so that the parts are in the position which they are intended to occupy when stored. The compactness of the device when thus folded will be obvious from this figure. Fig. 3 is a side view, partly in section, illustrating a modified construction of the file.

Like letters indicate like parts throughout the drawings.

Referring particularly to Figs. 1 and 2, A is a base-plate provided with a suspending ring A' and secured to the back B of the file.

B' is the cover of the file, provided with a slot to clear the wires and base-plate, as is customary. Two stout wire filing-arms C and D, so shaped as to form the opposite halves of an arch, are pivoted to the base-plate A, so as to be capable of turning about an axis parallel with the base-plate and close up to it, the inner ends C' D' of the wires being bent at right angles, as shown, and received within a metal tube E, which contains a spring F, placed in compression between the ends C' D', so as to tend always to separate them. The tube E is itself held in the desired position on the base-plate A by clips A² A³, formed upon the latter, and two abutments A⁴ A⁵ limit the movement of the wires C D away

from the tube E. The abutments A⁴ A⁵ have grooves A⁶ therein, so disposed as to receive the inner ends of the arched portions of the wires and maintain them normally in the position in which they are shown in full lines in Fig. 1—that is to say, in the position at right angles to the base-plate A.

If it be desired to remove a paper from the wire D, the wire C is first forced toward the wire D, and thus moved out of the groove A⁶ in the abutment A⁴ against the resistance of the spring F within the tube E, after which it can be readily turned to one side into the position in which it is indicated by dotted lines in Fig. 1.

If the file is to be folded for stowage, both the wires C and D are forced toward each other out of the grooves A⁶ in the abutments A⁴ A⁵ against the resistance of the spring F, and can then be turned over approximately into the plane of the base-plate A, as shown in Fig. 2, so as to lie quite flat upon the outside of the cover B', which itself lies flat against the back B, as shown.

The outer end of the wire C is beveled or grooved, as at c, against which the outer adjacent end d of the wire D may lie when the wires are in the position seen in full lines in Figs. 1 and 2.

Modifications may be made in the device without departure from the spirit or scope of the invention. For instance, as shown in Fig. 3 of the drawings, the upper arm might consist of a flat plate G, projecting at right angles from the base-plate on a level with the tip of the lower wire or arm D, in which case the latter is arranged to fold over sidewise, as in the first-described construction, the upper arm or plate being arranged to fold down, so as to lie parallel with the base, being normally pressed in that direction (indicated by the arrow) by a coil-spring H on the pivot of the plate G, one end of the spring bearing against the base and the other end against the upper edge of the plate or arm G.

Two or more arms or pairs of arms can be employed on the back instead of the single arm or single pair hereinbefore referred to.

What I claim, and desire to secure by Letters Patent, is—

1. In a letter-file, the combination with a base or support, and filing-arms pivotally con-

nected with the support, of a spring carried by the support and compressed between the inner ends of the arms and tending to press said arms apart, and stops for limiting the 5 movement of the arms away from each other.

2. In a letter-file, the combination with a base or support, of filing-arms having angularly-bent inner ends, a tube carried by the support into which tube the said bent ends 10 of the arms project, a spring within the tube and bearing upon the bent ends of the arms and a stop on the support both above and below the tube against which the arms are pressed by the spring.

15 3. In a letter-file, the combination with a base or support, of a pair of grooved abutments A⁴ A⁵, a tube E, filing-arms C, D, pivoted in the tube and movable in the direction of its axis, and means to keep the arms 20 and abutments in engagement.

4. In a letter-file, the combination with a base or support, and a stop, of independent filing-arms arranged one above the other in substantially the same vertical plane and normally 25 extending at substantially right angles to the support, one of said arms having a pivotal connection with the support and adapted to be moved first in a direction toward the other arm to free it from the stop and then 30 to be swung upon its pivot laterally toward

the face of the support, and a spring arranged to act upon the pivoted arm so as to tend to force the latter away from the other arm and to hold the pivoted arm in engagement with the stop when said pivoted arm is in its normal position over the other arm, substantially as described. 35

5. In a letter-file, the combination with a base or support, and stops, of filing-arms each pivotally connected with the support and 40 adapted to be normally held by the stops in a position at right angles to the support, said arms being arranged one above the other in substantially the same vertical plane, and each arm being adapted to be moved toward 45 the other arm to free it from its respective stop and to be swung upon its pivot laterally toward the face of the support, and a spring arranged to act upon both arms to tend to force the same in opposite directions and to 50 cause them to engage their stops when in normal position one above the other, as described.

In witness whereof I have hereto set my hand in the presence of the two subscribing 55 witnesses.

HERBERT PRICE LAVENDER.
